(Cl. D71—1)

To all whom it may concern:

Be it known that we, John K. Northrop, Walter J. Cerny and Fred J. Baum, citizens of the United States, residing in Los Angeles, in the county of Los Angeles and State of California, and Albert M. Schwartz, a citizen of the United States, residing in Palos Verdes, in the county of Los Angeles and State of California, have invented a new, original, and ornamental Design for an Airplane, of which the following is a specification, reference being had to the accompanying drawings, forming a part thereof.

Fig. 1 is a perspective view of an airplane showing our new design;

Fig. 2 is a side elevational view with landing gear extended;

Fig. 3 is a perspective view looking upwardly from underneath the airplane;

Fig. 4 is a front elevational view, with landing gear shown extended; and

Fig. 5 is a top plan view.

We claim:

The ornamental design for an airplane, as shown.

JOHN K. NORTHROP.
